Inventor:
Garrett W. Mudd
By *John F. Jackson Jr. Atty.*

UNITED STATES PATENT OFFICE.

GARRETT W. MUDD, OF CHICAGO, ILLINOIS.

INTERLACING MACHINE.

Application filed November 24, 1924. Serial No. 752,044.

To all whom it may concern:

Be it known that I, GARRETT W. MUDD, a citizen of the United States, residing at Chicago, in the county of Cook and State 5 of Illinois, have invented certain new and useful Improvements in Interlacing Machines, of which the following is a specification.

This invention relates to improvements in 10 interlacing machines for fibrous materials, particularly adapted though not necessarily limited in its use for curled hair, and one of the objects of the invention is to provide an improved machine of this character in 15 which the material fed into the machine will be gradually compressed as it arrives in position to be operated upon by the needles.

A further object is to provide improved 20 means whereby the density of the material to be operated upon by the needles may be varied at will.

A further object is to provide improved 25 means whereby the position of the needles or the angle at which the needles enter the material to be interlaced may be varied, and improved means whereby the extent of movement of the needles in the direction of travel of the material may be varied at 30 will.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

40 Figure 1 is a view in elevation taken from the left hand side of a machine of this character constructed in accordance with the principles of this invention.

45 Figure 2 is a view in elevation taken from the right hand side of Figure 1 and on line 2—2.

Figure 3 is an enlarged detail sectional view, taken on line 3—3, Figure 2.

50 Figure 4 is a detail, horizontal, sectional view taken on line 4—4, Figure 1, with parts omitted and parts broken away.

Figures 5, 6 and 7 are diagrammatic views illustrating the different steps and the movement of the needle and the material.

Figure 8 is a diagrammatic view showing 55 the path of movement of the needle.

Referring more particularly to the drawings the numeral 10 designates generally a supporting structure of any desired size and configuration and of any desired height. 60 Extending above the structure 10 is a superstructure embodying end walls 11 and 12 and a back wall 13, which latter terminates preferably short of the base of the superstructure and may be of an imperforate 65 construction or of a perforated construction as desired and according to the operation to be performed in the machine.

A front plate or member 14 is arranged in the superstructure and constitutes the 70 front of a hopper. This plate or member 14 is preferably transparent and is constructed of glass mounted in a suitable frame. The plate thus formed is supported for movement toward and away from the 75 rear plate 13 in any desired or suitable manner, preferably by means of bearings 15 and 16, slidably respectively in suitable guideways 17 and 18, and the bearings 15 and 16 are preferably located respectively adjacent 80 the upper and lower edges of the plate or member 14. These bearings are arranged adjacent the end walls 11 and 12 and may be moved in their guideways in any desired or suitable manner, such as by means of 85 sprocket wheels 19 and 20 threaded respectively upon bars or rods 21 and 22, connected respectively with the bearings 15 and 16, so that as the respective sprocket wheels are rotated the bearings 15 and 16 will be 90 moved forwardly or backwardly in their guides according to the direction of rotation of the sprocket wheels, the sprocket wheels being held against movement with the rods 21 in any suitable manner.

95 The sprocket wheels may be rotated in any suitable manner such as by means of a sprocket chain 23, which passes over the sprockets 19 and 20 and may if desired, pass over another or idle sprocket 24. An additional sprocket wheel 25 may also be provided over which the sprocket chain 23 passes, and a crank handle 26 may be connected with the sprocket wheel 25 for rotating the latter.

100 It will thus be seen that when the crank handle 26 is operated the sprocket chain 23 will rotate the sprockets 19 and 20 and the

bearings 15 and 16 will be moved in their respective guideways.

The adjustment of the plate or member 14 in this manner varies the size of the 5 hopper into which the material to be interlaced may be fed in the usual manner.

It is customary in machines of this character to blow the material into the hopper and with the improved construction herein 10 described the air, in the event that the back or plate 13 of the hopper is imperforate, will find its way through the top and bottom of the hopper.

In the event that the plate 13 is perforated 15 the air will find its way out of the hopper through the plate 13.

A feeding and compressing mechanism is provided for the material adjacent the bottom of the hopper and preferably beneath 20 the plate or member 14, so as to gradually compress the material to the desired density by the time it is in position to be acted upon by the interlacing needles, to be hereinafter described.

25 The feeding and compressing mechanism preferably consists of a plurality of endless flexible members 27 preferably in the form of chains which pass over sprocket wheels 28 loosely mounted upon a shaft 29 and laterally spaced from each other to any desired extent by any suitable means. The shaft 29 is preferably located adjacent the lower end of the plate or member 14 and is journaled in the bearings 16. The chains 27 also pass 30 over sprockets 30 connected with a shaft 31 journaled in suitable bearings 32, adapted to move in suitable guideways. If desired suitable belt tighteners 33, pivotally mounted as at 34, may be provided for maintaining 35 the endless elements 27 taut and are adapted to operate preferably upon one of the runs of the endless elements 27, an elastic member or spring 35 being provided for holding the belt tighteners yieldably in position.

40 The bearings 32, in which the shaft 31 is journaled, are adapted to be moved forwardly and backwardly in their guideways in any suitable manner but preferably in a manner similar to the manner in which the bearings 15 and 16 are moved in their guideways, that is by means of sprocket wheels 36-37 threaded upon a bar or rod 38 connected with the respective bearings. A chain 45 39 passes over these sprockets 36 and 37 and also preferably over another sprocket 40, a handle 41 being connected preferably with the sprocket 40, which latter is mounted upon any suitable fixed portion of the 50 superstructure, for rotating the sprocket and when rotated, the chain 39 will rotate the sprockets 36 and 37 for moving the bearings 32 backwardly and forwardly in their guideways.

55 With this improved construction it will

be manifest that the upper ends of the flexible elements 27, as well as the lower ends thereof may be moved forwardly and backwardly to vary the compression of the material and also to vary the thickness of the 70 pad to be formed. It will be manifest that the bearings 32 may be moved forwardly or backwardly independently of the bearings 16.

The endless flexible elements 27 are adapted to be actuated intermittently in any suitable manner, preferably by means of a ratchet gear 42 connected with the shaft 31 for rotation therewith. An arm 43 is pivotally supported, preferably intermediate 75 its ends, upon the shaft 31 and carries a pawl 44 which co-operates with the ratchet gear 42. The other end of the arm 43 is provided with a plurality of openings 45 by means of which the end of a rod 46 may be adjustably connected with the arm so as to vary the rocking movement of the arm 43 about its pivot and consequently the extent of the step by step or intermittent rotation of the ratchet gear 42. As this ratchet gear 42 is rotated the sprockets 30 will be correspondingly rotated to feed or move the endless flexible elements 27.

80 The other end of the rod 46 is connected preferably by means of an eccentric strap 47 with an eccentric 48 secured to a shaft 49, and which shaft is rotated in any suitable manner preferably by means of an endless flexible element 50 preferably in the form of a sprocket chain which passes over a suitable sprocket or pulley on the shaft 49.

85 The element 50 also passes over a pulley or sprocket wheel 51, which has connected with it a pulley 52, which latter receives its motion from any suitable source, preferably 90 a motor (not shown) and through the medium of a driving belt or connection (not shown).

95 It will thus be seen that when the pulley 52 is rotated the shaft 49 will be correspondingly rotated, and through the medium of the eccentric 48 and connecting rod 46, the arm 43 will be oscillated and will thereby impart an intermittent feeding movement to the endless flexible elements 27.

100 Endless flexible elements 53 may be provided for assisting in feeding the material through the hopper and to the interlacing needles. These elements 53 may be of any desired construction and any suitable number may be employed, but are preferably of a cable like formation and pass over suitable drums or pulleys 54 at the top of the hopper and over a drum 55 and an idle drum or pulley 56. The elements 53 are so arranged that one of the runs thereof will pass through the hopper in a plane parallel with the back and with the face of the member or plate 14 and below the hopper 105 to a point below the lower extremity of the 110

flexible elements 27 and are adapted to stand in close proximity or rest against the rear wall 13 of the hopper. These elements 53 cooperate with the elements 27 for feeding 5 the material.

The elements 53 are preferably given an intermittent movement in any suitable manner such as by means of a ratchet gear 57 connected with the shaft 58, to which the 10 drum 55 is connected. An arm 59 is preferably pivotally supported intermediate its ends upon the end of the shaft 58 and carries a dog or pawl 60 which co-operates with the teeth of the ratchet wheel 57. The 15 other end of the arm is provided with a plurality of openings 61, and by means of which openings one end of a rod 62 is adjustably connected with the arm so as to vary the extent of oscillating movement of the arm. 20 The other end of the arm 62 is connected preferably with the bar or rod 46 by means of a clip or collar 63 so that the arm 59 will be rocked by the bar or rod 46 through the medium of the bar or rod 62. 25 With this construction it will be manifest that any degree of intermittent movement may be imparted to the elements 53 and 27, and if desired the extent of movement of these elements may be varied with respect 30 to each other or their movement may be maintained uniform.

Arranged in rear of the hopper and preferably in rear of the plate 13 is a needle bar 64, having a plurality of needles 65 35 detachably connected thereto and secured in position by means of suitable fastening bolts 66.

The ends of the needle bar are journaled in rollers 67, and which rollers travel in 40 guideways 68, and in which guideways the bearings for the shaft 31 also travel.

The rollers 67 are loosely mounted upon the ends of the needle bar 64 so that when the rollers are moved forwardly and back- 45 wardly in the guideways they will roll upon the walls of the guideways and advance and retract the needle bar 64, at the same time the needle bar is adapted for a rocking movement about the axes of the rollers.

50 The forward and backward movement of the needle bar may be accomplished through the medium of connecting rods 69, preferably one on each end of the bar 64, and one end of these rods 69 is pivotally connected 55 to the bar. The other ends of the rods 69 are connected with cranks 70 carried by a shaft 71 mounted in suitable bearings, and one of which cranks 70 may constitute a portion of the pulley 52.

60 An oscillating movement may be imparted to the needle bar 4 in any suitable manner but preferably from a cam 72, which is connected with the shaft 49 for rotation therewith. The needle bar is preferably pro- 65 vided with a projecting portion 73 having a

bifurcation 74, the walls of the bifurcation being provided with openings 75 and by means of which openings a connecting rod 76 is adjustably connected to the needle bar by one extremity as at 77. The other end 70 of the bar 76 is pivotally connected as at 78 with the member 79, the latter being pivotally supported as at 80 upon a fixed support and is of any desired construction. This member 79 projects for a considerable 75 distance over and beyond the shaft 49 and is provided with an anti-friction roller 81 against which the cam travels. The member 79 is provided with a number of openings 82 so that the end of the bar or rod 76 80 may be adjustably connected thereto to vary the position or the point of connection therewith with respect to the pivot 80 and thereby control or vary the extent of oscillating movement of the needle bar 64 85 about its pivots formed with the rollers 67.

It will thus be manifest that as the shaft 71 is rotated the needle bar will be reciprocated forwardly and backwardly and as the cam 72 rotates the needle bar will be oscillated upwardly and downwardly through the medium of the member 79 and the connecting bar or rod 76. 90

Obviously the parts operate in timed relation with respect to each other. 95

It is sometimes desired to interlace the material 83 with a backing 84 (see particularly Figures 5 to 7), such as burlap or the like, and in that event the burlap may be 100 felt from any suitable supply and in a direction downwardly through the top of the hopper.

The burlap may be used in connection with the endless members 53 or these members 53 may be removed when the burlap is used. (Obviously any backing suitable for the purpose may be employed instead of burlap.) When the members 53 are used they will assist in advancing the burlap with the material being operated upon but when the members 53 are not employed the burlap will be advanced by the operation of the needles 65 thereupon. 110

The operation of the mechanism is as follows. Assuming the parts to be in the position shown in Figure 3, that is with the needle bar retracted the material will be fed through the hopper and will be compressed as it advances or is positioned to be acted upon by the needles. The needles are then advanced through the medium of the crank pins 70 until the needles penetrate the material and assume the position shown in full lines in Figure 5 and in a direction indicated by line A in Figure 8. The cam 72 will then rock the needle bar 64 to lower the needle to the position shown in dotted lines in Figure 5, and in a direction indicated by the line B in Figure 8, that is in the general direction of feeding move- 125 130

ment of the material. The needle is then retracted to the position shown in full lines in Figure 6 and in the direction indicated by the line C in Figure 8, until the hook 5-85 of the needle is brought to a position in close proximity to the backing 84. After the needle has penetrated the backing 84 and assumed the position shown in full lines in Figure 5, and during the movement of 10 the needle from the full line position in Figure 5 to the dotted line position in Figure 5, the material 83 and the backing 84 will be advanced by the action of the needle. After the needle assumes the position shown in full lines in Figure 6 the cam 72 will then operate to raise the needle slightly to the position shown in dotted lines in Figure 6 and in the direction indicated by the line D in Figure 8. This step of 20 movement is given to the needle so as to raise the end of the hook portion 85 of the needle sufficiently to permit it to pass through the opening formed in the backing 84 by the penetration of the needle. At the 25 same time a portion of the material 83 will be drawn through the body of the material and through the opening in the backing 84, and as shown at 86 in Figure 7 of the drawings. The movement of the needle 65 in 30 withdrawing the needle and pulling the portion 86 of the material through the opening in the backing 84 is indicated by the line E in Figure 8.

The needle bar 64 is then rocked about 35 its pivot by the cam 72 to raise the needle in a direction indicated by the line F in Figure 8, which is the limit of the rearward movement of the needle. This last 40 step of operation will disengage the needle from the portion 86 of the material which is pulled through the body of the material and through the backing 84, when the latter is employed.

The operation of the needle and the paths 45 of movement thereof are the same whether the backing 84 is employed or not.

With this improved construction it will be manifest that there will be provided a machine in which a mat or pad of uniform 50 thickness and density may be provided while the machine is adapted to vary at will the density of the material at the point at which it is being interlaced.

The variations of the position of the 55 plate or member 14 will also provide for a variation in the volume of material per square foot.

Furthermore the extent of the feeding 60 movement of the backing 84 is controlled by the extent of the downward movement of the needles 65, and this extent of movement of the needles in turn may be varied by the adjustment or variation of the points of connection of the ends of the bar or rod 76 65 with the needle bar and the member 79.

By the arrangement of the hopper in a vertical position and by feeding the material vertically to the needles the material will be fed by gravity and will not disintegrate and settle away from the needles as would 70 be the case if the material is fed horizontally. Furthermore with the vertically arranged hopper the material, especially short hair, will fall so that it will lay and pile 75 in a position, while being interlaced, that when the pad is completed the hairs will stand on end, thereby imparting greater resiliency to the pad. A further advantage by the use of a vertically arranged hopper 80 results by reason of the fact that the hair may be interlaced in a looser condition and will not pack as when fed in a horizontal plane.

While the preferred form of the invention 85 has been herein shown and described, it is to be understood that various changes may be made in the details of construction and in the combination and arrangement of the several parts, within the scope of the claims, without departing from the spirit of this invention, and if found necessary or desirable it is to be understood that suitable belt 90 tighteners (not shown) may be employed in connection with the endless flexible elements 53.

What is claimed as new is:—

1. An interlacing machine including a hopper for the material, one wall of the hopper being adjustable to vary the size of the hopper, means adjacent the outlet of the hopper for compressing the material delivered therefrom, a reciprocating needle, and means for moving the said needle in the direction of feeding movement of the material after it has been inserted into the material.

2. An interlacing machine including a hopper for the material, one wall of the hopper being adjustable to vary the size of the hopper, means adjacent the outlet of the hopper for compressing the material delivered therefrom, a reciprocating needle, and means for moving the said needle in the direction of feeding movement of the material after it has been inserted into the material, the said needle operating to assist in advancing the material being operated upon.

3. An interlacing machine including a hopper for the material, means for varying the size of the hopper, means adjacent the outlet end of the hopper for gradually compressing the material delivered therefrom, means for varying at will the degree of compression exerted by the last recited means, a reciprocating needle support, means for reciprocating the needle support, and means for rocking the needle support in a vertical plane and in the direction of feeding movement of the material after the needle has been inserted into the material.

4. An interlacing machine including a hopper for the material, means for varying the size of the hopper, means adjacent the outlet end of the hopper for gradually compressing the material delivered therefrom, means for varying at will the degree of compression exerted by the last recited means, a reciprocating needle support, means for reciprocating the needle support, means for imparting a movement to the needle in the direction of feeding movement of the material, the said compressing means including an endless flexible element, means for imparting movement to the said element, and means for varying at will the position of the said element with respect to the parts co-operating therewith to vary the degree of compression exerted thereby. 70
5. An interlacing machine including a hopper for the material, one wall of the hopper being transparent, means for adjusting one of the hopper walls with respect to the other walls to vary the size of the hopper, means adjacent the outlet of the hopper for gradually compressing the material, a reciprocating needle bar, means for reciprocating the needle bar, and means for imparting a movement to the needle in the direction of the feeding movement of the material. 80
6. An interlacing machine including a hopper for the material, one wall of the hopper being transparent, means for adjusting one of the hopper walls with respect to the other walls to vary the size of the hopper, means adjacent the outlet of the hopper for gradually compressing the material, a reciprocating needle bar, means for reciprocating the needle bar, means for imparting a movement to the needle in the direction of feeding movement of the material, the said compressing means including an endless flexible element, and means for imparting movement to the said element. 85
7. An interlacing machine including a hopper for the material, one wall of the hopper being transparent, means for adjusting one of the hopper walls with respect to the other walls to vary the size of the hopper, means adjacent the outlet of the hopper for gradually compressing the material, a reciprocating needle bar, means for reciprocating the needle bar, means for imparting a movement to the needle in the direction of feeding movement of the material, the said compressing means including an endless flexible element, means for imparting intermittent movement to the element, and means whereby the extent of the movements of the said element may be varied. 100
8. An interlacing machine including a hopper for the material, one wall of the hopper being transparent, means for adjusting one of the hopper walls with respect to the other walls to vary the size of the hopper, means adjacent the outlet of the hopper for gradually compressing the material, a reciprocating needle bar, means for reciprocating the needle bar, means for imparting a movement to the needle in the direction of feeding movement of the material, and means for assisting in feeding the material through the hopper and to the said compressing means, the said feeding means including an element traveling through the hopper. 105
9. An interlacing machine including a hopper for the material, means adjacent the outlet of the hopper for compressing the material delivered therefrom, a reciprocating needle bar, means for reciprocating the needle bar, means for imparting a movement to the needle in the direction of feeding movement of the material, and means operating to assist in feeding the material through the hopper and to the said compressing means. 110
10. An interlacing machine including a hopper for the material, means adjacent the outlet of the hopper for compressing the material delivered therefrom, a reciprocating needle bar, means for reciprocating the needle bar, means for imparting a movement to the needle in the direction of feeding movement of the material, means operating to assist in feeding the material through the hopper and to the said compressing means, and means for imparting an intermittent movement to the said feeding means. 115
11. An interlacing machine including a hopper for the material, means adjacent the outlet of the hopper for compressing the material delivered therefrom, a reciprocating needle bar, means for reciprocating the needle bar, means for imparting a movement to the needle in the direction of feeding movement of the material, and means operating to assist in feeding the material through the hopper and to the said compressing means, the said feeding means including an element traveling through the hopper. 120
12. An interlacing machine including a hopper for the material, means adjacent the outlet of the hopper for compressing the material delivered therefrom, a reciprocating needle bar, means for reciprocating the needle bar, means for imparting a movement to the needle in the direction of feeding movement of the material, means operating to assist in feeding the material through the hopper and to the said compressing means, the said feeding means including an endless flexible element traveling through the hopper, and means for imparting an intermittent movement to the said element. 125
13. An interlacing machine including a hopper for the material, means adjacent the outlet of the hopper for compressing the material delivered therefrom, a reciprocating needle bar, means for reciprocating the needle bar, means for imparting a movement to the needle in the direction of feeding movement of the material, and means for assisting in feeding the material through the hopper and to the said compressing means, the said feeding means including an element traveling through the hopper. 130

- ing needle bar, means for reciprocating the needle bar, means for imparting a movement to the needle in the direction of feeding movement of the material, means operating to assist in feeding the material through the hopper and to the said compressing means, the said means including an endless flexible element traveling through the hopper, and means for imparting an intermittent movement to said element, the last recited means including means whereby the extent of the movements of the said element may be varied.
14. An interlacing machine including a hopper for the material, one wall of the hopper being adjustable, means for adjusting said wall to vary the volume of the material to be operated upon, the wall opposite the adjustable wall extending beyond the end of the latter, an endless flexible element forming a continuation of the said adjustable wall, means for actuating the said element, a reciprocating needle bar, means for reciprocating the bar to cause the needle carried thereby to penetrate the material and to be withdrawn therefrom, and means for imparting a movement to the needle in the direction of feeding movement of the material and while the needle is operating upon the work.
15. An interlacing machine including a hopper for the material, one wall of the hopper being adjustable, means for adjusting said wall to vary the volume of the material to be operated upon, the wall opposite the adjustable wall extending beyond the end of the latter, an endless flexible element forming a continuation of the said adjustable wall, means for actuating the said element, a reciprocating needle bar, means for reciprocating the bar to cause the needle carried thereby to penetrate the material and to be withdrawn therefrom, means for imparting a movement to the needle in the direction of feeding movement of the material and while the needle is operating upon the work, and means whereby the extent of said additional movements of the needle may be varied.
16. An interlacing machine including a hopper for the material, one wall of the hopper being adjustable, means for adjusting said wall to vary the volume of the material to be operated upon, the wall opposite the adjustable wall extending beyond the end of the latter, and endless flexible element forming a continuation of the said adjustable wall, means for actuating the said element, a reciprocating needle bar, means for reciprocating the bar to cause the needle carried thereby to penetrate the material and to be withdrawn therefrom, means for imparting a movement to the needle in the direction of feeding movement of the material and while the needle is operating upon the work, and means for assisting in feeding the material through the hopper.
17. An interlacing machine including a hopper for the material, one wall of the hopper being adjustable, means for adjusting said wall to vary the volume of the material to be operated upon, the wall opposite the adjustable wall extending beyond the end of the latter, an endless flexible element forming a continuation of the said adjustable wall, means for actuating the said element, a reciprocating needle bar, means for reciprocating the bar to cause the needle carried thereby to penetrate the material and to be withdrawn therefrom, means for imparting a movement to the needle in the direction of feeding movement of the material and while the needle is operating upon the work, and means for bodily adjusting the said element in directions transverse to the direction of feeding movement of the material to vary the compression of the material.
18. An interlacing machine including a hopper for the material, one wall of the hopper being adjustable, means for adjusting said wall to vary the volume of the material to be operated upon, the wall opposite the adjustable wall extending beyond the end of the latter, an endless flexible element forming a continuation of the said adjustable wall, means for actuating the said element, a reciprocating needle bar, means for reciprocating the bar to cause the needle carried thereby to penetrate the material and to be withdrawn therefrom, means for imparting a movement to the needle in the direction of feeding movement of the material and while the needle is operating upon the work, and means for assisting in feeding the material through the hopper.
19. An interlacing machine including a hopper for the material, one wall of the hopper being adjustable, means for adjusting said wall to vary the volume of the material to be operated upon, the wall opposite the adjustable wall extending beyond the end of the latter, an endless flexible element forming a continuation of the said adjustable wall, means for actuating the said element, a reciprocating needle bar, means for reciprocating the bar to cause the needle carried thereby to penetrate the material and to be withdrawn therefrom, means for imparting a movement to the needle in the direction of feeding movement of the material and while the needle is operating upon the work, an endless flexible traveling element through the hopper for assisting in feeding the material, and means for imparting an intermittent movement to the last recited element.

20. An interlacing machine including means for supplying the material, means for compressing the material, a backing adapted to travel with the material, a reciprocating needle, means for reciprocating the needle in directions transverse to the direction of feeding movement of the material to penetrate the said backing and the material and to withdraw the needle, and means for imparting to the needle during the time that the needle is operating upon the material, a movement in the direction of the feeding movement of the material, during a portion of the interlacing operation, said needle during the last recited movement operating upon the said backing to advance the latter with the material.
21. An interlacing machine including means for supplying the material, means for compressing the material, a backing adapted to travel with the material, a reciprocating needle, means for reciprocating the needle in directions transverse to the direction of feeding movement of the material to penetrate the said backing and the material and to withdraw the needle, means for imparting to the needle during the time that the needle is operating upon the material, a movement in the direction of the feeding movement of the material, during a portion of the interlacing operation, said needle during the last recited movement operating upon the said backing to advance the latter with the material, and means whereby the extent of the last recited movement of the needle may be varied.
22. An interlacing machine including means for supplying the material, means for compressing the material, a backing adapted to travel with the material, a reciprocating needle, means for reciprocating the needle in directions transverse to the direction of feeding movement of the material to penetrate the said backing and the material and to withdraw the needle, means for imparting to the needle during the time that the needle is operating upon the material, a movement in the direction of the feeding movement of the material, during a portion of the interlacing operation, said needle during the last recited movement operating upon the said backing to advance the latter with the material, and means for varying at will the position of the needle before it penetrates the said backing to vary the amount of material drawn through the said backing as the needle is removed.
23. An interlacing machine including a reciprocating needle, means for reciprocating the needle, the said means including mechanism for successively moving the needle in a direction transverse to and also in the direction of feeding movement of the material, and means for feeding the material to the needle in a vertical plane.
24. An interlacing machine including a vertically arranged hopper for the material, the material being fed from the hopper in a vertical plane, a needle, and means including mechanism for reciprocating the needle in a plane transverse to and also in the direction of the feeding plane of the material.
25. An interlacing machine including a vertically arranged hopper for the material, the material being fed from the hopper in a vertical plane, a needle, and means for imparting to the needle a movement in the direction of feeding movement of the material during the interlacing operation.
- In testimony whereof I have signed my name to this specification on this 12th day of November, A. D. 1924.

GARRETT W. MUDD.
